BOBBIN SUPPORT.

Application filed August 12, 1928. Serial No. 128,778.

This invention relates to bobbin supports and aims to provide an improved means for mounting roving bobbins on the creels of spinning frames and the like.

It has long been customary to mount the roving bobbins on the creel boards of a spinning frame by passing a creel skewer through each bobbin, inserting the upper end of the skewer in a hole in the upper creel board, and resting the lower end of the skewer in a cup on the lower creel board. This form of mounting possess serious disadvantages in that it does not permit free rotation of the bobbins and, in particular, it retards the rotation of the bobbins after lint has collected in the cup in which the lower end of the skewer rests. The skewer mounting, therefore, causes a back draft on the rovings in addition to the intended draft of the drawing rolls, and this back draft, being irregular, causes irregular stretching of the rovings, which results in the failure to produce uniform yarns.

An object of the present invention is to mount the bobbins so as to eliminate objectionable back draft on the rovings. A further object is to facilitate the cleaning of the creel boards and the changing of the bobbins, thus reducing the amount of labor required in tending a spinning frame. A still further object is to provide an improved bobbin support which may easily be applied to the creel boards of existing spinning frames.

In a device embodying the invention in a form which we now consider most desirable, these objects are attained by providing a bobbin support which has a freely rotatable bobbin holder depending from an upper creel board of the frame. The rotatable holder is adapted to enter the upper end of the bore of a bobbin, and is provided with resilient means for holding the bobbin by engagement with its inner surface. The length of the holder is materially less than that of a bobbin, and is no greater than the difference between the distance which separates the creel boards, and the length of a bobbin. The bobbins may, therefore, easily be applied to and removed from the holder. When a bobbin is on a holder, its lower end is entirely free and is some distance above the lower creel board, so that it in no way interferes with the cleaning of the creel board, and so that any lint

which may collect on the creel board before cleaning can in no way interfere with or retard the rotation of the bobbin.

The depending rotary holder is mounted on a combined thrust and rotary bearing, which is positioned inside the bobbin near its upper end and, consequently, well above the middle of the bobbin. Means are provided to prevent wabbling of the holder during its rotation. Because of the resilient character of the means by which it is held, the bobbin is free to tip slightly with respect to the bearing of the holder. The bearing is of the anti-friction type so that the holder and bobbin rotate freely without causing any material back draft on the roving, while, at the same time, it results from the fact that the collection of lint cannot retard the rotation, and the fact that the bobbin rotates without wabbling, that such slight back draft as exists is substantially uniform, and, therefore, causes substantially no irregularity in the yarn.

Other objects and advantages of the invention are hereinafter explained in connection with a detailed description of a specific bobbin support embodying the invention. In the accompanying drawings,

Fig. 1 is a transverse sectional elevation of the upper part of a spinning frame of usual construction showing the creel provided with bobbin supports embodying the invention;

Fig. 2 is a large scale axial section of one of the bobbin supports shown in Fig. 1, showing part of a bobbin supported by it; and

Fig. 3 is a section on the line 3—3 of Fig. 2.

The bobbin support shown in the drawings has a central bolt or stud 10 threaded at its upper end and provided at its lower end with a flat head 11, preferably formed integral with the bolt. The bolt carries near its head, two oppositely-facing cones 12, 13, which provide the inner races for two sets of bearing balls 14, 15. Above the upper cone 13, the bolt carries a spacing sleeve 16, and above this sleeve is a dust cap 17 having a depending flange 19. The upper end of the bolt projects sufficiently above the dust cap to pass through a hole in the ordinary creel board D of a spinning frame and to project above the board sufficiently to permit the application of a nut 18 to the threaded upper end of the bolt. It should be noted that when this nut is tightened, it holds the bolt firmly in the creel

board, and holds the cones, spacing sleeve, and dust cap, all firmly in fixed position on the bolt.

Depending from the bearing provided by the cone 12, and the balls 14, is a rotary bobbin holder 20 which has the form of a sleeve whose external diameter is slightly less than the internal diameter of a roving bobbin. An internal annular boss 21 is provided in the sleeve 20 near its upper end. This boss projects inwardly between the balls 14 and 15, so as to provide the outer races for them, and to cooperate with the cones and balls in providing a bearing which resists end thrust and prevents wobbling of the bobbin holder. The upper end of the sleeve 20 lies just within the depending flange 19 of the dust cap 16.

Resilient means are provided to engage the inner surface of a bobbin and hold it upon the sleeve 20. To provide for such means, the portion of the sleeve 20 below the boss 21 is provided with two sets of diametrically opposite holes 22, 23. Two expansion members 24, 25 extend diametrically across the sleeve 20 and have their outer ends projecting through the holes 22, 23. Each expansion member consists of two headed rivets 26 and a compression spring 27. The heads of the rivets are provided with annular lips 29 which normally rest against the inner wall of the sleeve, and projecting hemispherical or conoidal bosses 30, which project through the holes in the sleeve. The stems of the rivets are surrounded by the spiral compression spring 27, which holds them in alignment. The inner ends of the stems are spaced a little distance apart.

The sleeve 20 is provided with a stop to prevent a bobbin placed on it from being pushed upon the sleeve far enough to bring its upper end into contact with the upper creel board, thus impeding its rotation. In the form shown, this stop consists of a spiral tension spring 32 extending around the annular groove 33, provided by the boss 21, and having its ends fastened together. This spring limits the extent to which a bobbin may be pushed up along the sleeve, by engaging the small internal shoulder S, with which roving bobbins R are provided near their upper ends. At the same time, the peripheral surface of this spring resiliently engages the enlarged bore of the bobbin above this shoulder, and thus cooperates with the expansion members 24, 25 in holding the bobbin securely upon the sleeve.

It should be noted that the bobbin holder which has been described may be manufactured at small costs, not only because of the simplicity of the parts of which it is composed, but also because it may be assembled easily in the following manner:

The bolt 10 is held with its head downward, and the cone 13 and the balls 14, held in a ball retainer, are placed around the bolt. The

sleeve 20 is then placed around the bolt and allowed to drop down until the boss 21 rests on the balls. The balls 15, the cone 13, the spacing sleeve 16, and the dust cap 17 are then placed about the bolt in the order stated. The 70 expansion members 24 and 25 are then bent and sprung into position with their heads in the holes 22, 23. The upper expansion member 25 serves to prevent the bolt 10 from dropping out of the sleeve, and this holds the parts 75 in assembled condition until they are firmly locked in position by the nut 18 when the bobbin holder is applied to a creel board.

The use of the device described is illustrated in Fig. 1, which shows the table A, the 80 thread board B; the drawing rolls C of a spinning frame of usual construction provided with three superimposed creel boards D, E, F, for supporting two tiers of roving bobbins. Bobbin supports of the form which has been described, are applied to the frame by inserting their bolts 10 in holes in the upper and middle creel boards D and E, so that their rotary holders 20 depend from these creel boards. It will be noted that the holders are so short that there is plenty of room between the lower end of each holder and the upper surface of the next creel board below, to permit the placing of roving bobbins on the holders, and their removal therefrom. It 90 will be noted also that the bobbins which are mounted on the holders have their lower ends entirely free and some distance above the next creel board below them, so that it is easy to remove lint which collects on the creel boards. It is apparent also that because of the fact that the bearings are at the upper ends of the bobbins and are protected by the dust caps, 95 lint can in no way retard the rotation of the 100 holders and bobbins.

While the new bobbin support is, as above explained, adapted for use with the creel boards of existing spinning frames, it is apparent that in new spinning frames designed to be equipped with the new bobbin supports, the lower creel board may be altogether omitted, and the upper and middle creel boards may be replaced by metal bars with holes for the bolts of the bobbin support. With this arrangement, all the lint from the roving 110 bobbins falls to the floor under the spinning frame so that the problem of cleaning the 115 creel boards is eliminated altogether.

What is claimed is:

1. A bobbin support for the creels of spinning frames and the like, comprising a fixed member carrying a bearing, a holder depending from said bearing and rotatable thereon and adapted to enter the one end of the bore of the roving bobbin, and means for retaining the bobbin on the holder so that the bobbin hangs with the end of its bore engaged by the holder uppermost.

2. The combination with the upper and lower creel boards of a spinning frame and 130

- a roving bobbin to be mounted thereon, of a freely rotatable holder depending from the upper creel board, adapted to enter the upper end of the bore of the bobbin, and so short that its lower end is separated from the lower creel board by a distance as great as the length of the bobbin so as to facilitate the application and removal of the bobbin, and resilient means on the holder to engage the inner surface of the bobbin. 3. A bobbin support for the creels of spinning frames and the like, comprising a sleeve adapted to extend into the bore of a roving bobbin from one end thereof and less than one-half the length of the bobbin, a fixed supporting member extending into said sleeve, and an anti-friction bearing between said member and sleeve. 4. A creel for supporting superimposed rows of bobbins, comprising two horizontal superimposed fixed supports separated by a vertical distance greater than the length of a roving bobbin but less than twice the length of a bobbin, vertical rotary holders mounted on one of said supports extending toward the other and adapted to enter and engage the bores of roving bobbins, said holders being so much shorter than the bobbins that their outer ends are separated from said other support by a distance as great as the length of a roving bobbin. 5. The combination with the creel of a spinning frame and a roving bobbin to be supported thereon, of a bobbin holder secured to the creel, projecting less than half way through the bobbin, and providing a combined thrust and rotary bearing within the bore of the bobbin near one end thereof. 6. A bobbin support for spinning frames and the like, comprising a hollow rotary holder entering one end of the bore of a bobbin, a fixed stud projecting into said hollow holder from its outer end, two closely spaced ball bearings between the stud and the holder near its outer end, and a resilient member near the inner end of the holder adapted to grip the inner surface of the bobbin. 7. A bobbin support, comprising a fixed stud, a sleeve surrounding the stud and adapted to enter the bore of a bobbin, a ball bearing between said stud and the inner surface of said sleeve, and a spring grip on said sleeve engaging the inner surface of the bobbin. 8. A bobbin support, comprising a hollow rotary holder having an internal annular boss, bearing balls engaging opposite sides of said boss, and a fixed stud extending into said holder and supporting said bearing balls. 9. A bobbin support, comprising a sleeve having an annular depression, a fixed stud extending into said sleeve, oppositely facing ball races supported on said stud at opposite sides of the depression in the sleeve, and two sets of bearing balls each located between said depression and one of said races. 10. A bobbin support, comprising a sleeve having an internal annular boss and diametrically opposite holes below said boss, a bolt extending into said sleeve and having a head at its inner end, oppositely facing ball races slidably mounted on said bolt, bearing balls between said races and said annular boss, and an expansion member extending between said diametrically opposite holes and projecting therethrough and serving to hold a bobbin on the sleeve and to prevent accidental removal of the bolt and ball races from the sleeve. 11. A bobbin holder, comprising a rotatably mounted sleeve containing diametrically opposite holes, and an expansion member comprising two rivets having heads projecting outwardly through said holes, and a compression spring surrounding the stems of said rivets and serving to hold the stems of the rivets in alignment and to force the heads of the rivets apart. 12. A bobbin support, comprising a rotatably mounted holder adapted to extend within the smaller bore of a bobbin which is provided with an internal shoulder near one of its ends, a spring grip on said holder engaging the smaller part of the bore of the bobbin, and a stop on the outer surface of said holder engaging the internal shoulder of the bobbin to limit the extent to which the bobbin may be slipped upon the holder. 13. The combination with a roving bobbin having a slightly enlarged bore near one end, of a bobbin holder comprising a sleeve containing an annular groove, resilient expansion grips on said sleeve beyond said groove adapted to engage the smaller bore of the bobbin, and a coiled spring extending around the groove and adapted resiliently to engage the larger bore of the bobbin and the shoulder between the two bores thereof. 14. A bobbin support, comprising a sleeve having an annular depression, a fixed member extending within the sleeve, ball bearings between said fixed member and opposite sides of the boss provided by the inner surface of said groove, and a spiral spring extending around said groove and projecting beyond the outer surface of the bobbin. 15. A bobbin support comprising a depending rotary holder mounted on a bearing located above the center of gravity of the bobbin and resiliently engaging the bobbin to permit a tipping of its axis with respect to the axis of the bearing. 16. A bobbin support for the creels of spinning frames and the like, comprising a ball bearing, means for supporting said ball bearing with its axis vertical, and means for suspending a bobbin from said ball bearing so that it hangs vertically therefrom. 17. A bobbin support for the creels of

spinning frames and the like, comprising a ball bearing, means for supporting said ball bearing with its axis vertical, means for suspending a bobbin from said ball bearing so that it hangs vertically therefrom, and means for preventing the bobbin from wabbling about the axis of the bearing.

18. A bobbin support for the creels of spinning frames and the like, comprising a ball bearing, means for supporting said ball bearing with its axis vertical, and a bobbin holder suspended from said ball bearing and adapted to enter and grip one end of the bore of a bobbin so that the bobbin hangs vertically with its gripped end uppermost.

19. A bobbin support for the creels of spinning frames and the like, comprising a ball bearing, means for supporting said ball bearing with its axis vertical, a bobbin holder suspended from said ball bearing and adapted to enter and grip one end of the bore of a bobbin so that the bobbin hangs vertically with its gripped end uppermost, and means for preventing said holder from wabbling about the axis of said ball bearing.

In testimony whereof we have hereunto set our hands.

JOHN V. MANN.
LOUIS B. HASBROUCK.
